Primary Examiner—Robert R. Song

[57] ABSTRACT

A pneumatic mechanism for lifting generally heavy appliances such as a washing machine from a stationarily supporting leg structure so as to be supported on casters to provide ready portability. The mechanism includes an air inflatable member disposed between a generally horizontal bottom wall of the appliance housing and a lower movable support plate having a plurality of attached casters. The support plate is mounted on the bottom wall for limited vertical movement as guided by rods and biased to a retracted position in close proximity to the bottom wall by springs to normally retain the plate and casters well above the floor in which the appliance rests. Inflation of the inflatable member causes the support plate to move downwardly, against the force of the springs, until the casters contact the floor. Further inflation lifts the appliance so as to be supported on the casters for easy manual portability. The guide rods, in addition, to guiding the vertical movement of the support plate, limit the amount of vertical movement and provide rigidity to the mechanism when in an inflated position. The inflatable member includes a valve which can be opened to release the air and deflate the member to once again lower the machine to its stationarily supporting leg structure.

PNEUMATIC LIFTING MECHANISM

This is a continuation of application Ser. No. 303,580 filed Nov. 3, 1972, now abandoned.

BACKGROUND OF THE INVENTION

1. Field of the Invention

The invention relates to a mechanism for transferring the weight of a normally stationarily supported appliance to support structure providing easy portability of the appliance, and more particularly to a pneumatic means, disposed between a bottom wall of the appliance housing and the supporting surface such as a floor, which is inflatable to a sufficient dimension to lift the machine from resting on the leg structure depending from the housing to casters associated with the mechanism.

2. DESCRIPTION OF THE PRIOR ART

Various mechanisms for providing relatively easy portability of heavy household appliances are well known in the art. Such mechanisms however must also include some means of preventing unwanted movement of the appliance which can be induced from the vibration produced as the appliance operates. Therefore, to satisfy the requirements of portability yet provide a generally stationary support even under extreme operating conditions, such as an automatic washing machine having an uneven load distribution during the spin dry cycle, the structure provided generally either permanently supported the weight of the appliance on casters with a manually actuated braking mechanism for the casters which maintained the appliance generally stationary, or, included a mechanism which would transfer the weight of the appliance from structure such as legs providing the stationary support to structure providing ready portability, which in most instances, included casters.

The first mentioned mechanism, although generally the least expensive, had a disadvantage in that the casters' surface tended to become flattened from supporting the machine which in turn, over the life of the machine, substantially effected their ability to roll.

The second mentioned mechanisms, although alleviating this disadvantage of the first, were generally more expensive in that they required some lifting mechanism to transfer the weight, and in the highly competitive atmosphere of the appliance marketplace were prohibitively expensive. U.S. Pat. Nos. 2,671,242, 3,610,364, and 3,635,491 are exemplary of rather expensive weight transferring devices to provide appliance portability.

SUMMARY OF THE INVENTION

This invention relates to a simple and relatively inexpensive mechanism to transfer the support of an appliance from legs providing stationary support to casters to provide easy manual portability and includes an inflatable diaphragm or tube interposed between the bottom wall of an appliance housing and a normally retracted support plate attached to the bottom wall through guide rods which permit a limited vertical movement of the support plate. The surface of the support plate facing the floor supports a plurality of casters. Inflation of the diaphragm to a sufficient pressure initially forces the support plate from a retracted position to a position forcing the casters against the floor. Further inflation will thus lift the appliance from the

generally stationarily supporting legs so that the appliance is then supported on the casters for rolling portability. Continued inflation forces the plate to the maximum position limited by the guide means at which point the diaphragm and the guide means cooperate to provide required rigidity to the inflated support structure. Further, spring means are interposed between the bottom wall and the support plate to generally oppose the movement caused by inflating the diaphragm so that upon deflating the diaphragm the plate is retracted to a position elevating the casters above the floor.

BRIEF DESCRIPTION OF THE DRAWINGS

FIG. 1 is an elevational cross-section of the lifting mechanism of the present invention attached to a laundry appliance;

FIG. 2 is an enlarged view of a portion of FIG. 1; and

FIG. 3 is a bottom plan view of the lifting mechanism as attached to the laundry appliance of FIG. 1.

DESCRIPTION OF THE PREFERRED EMBODIMENTS

Lifting mechanisms such as the present invention are used in many appliances; however, the present invention is disclosed in a center post agitator washing machine 10, which, as shown in FIG. 1, includes a housing 12 generally enclosing the operating mechanisms of the appliance which are well known in the art. The housing also includes a bottom wall 14, which, in this case, is contoured so as to provide utility in the pivotal support of the washing machine's tubs and drive mechanism. However, it is acknowledged that the bottom wall 14 could generally be of any desired configuration from planar to a contoured configuration such as shown. The appliance is generally stationarily supported by adjustable leg bolts 16 and a mating nut 18 secured to the bottom wall 14 to provide variable lengths to the support legs so that they can be adjusted to maintain the machine in a substantially level position. Locking means such as lock nuts 20 are provided for tightening the bolts once their properly extended position has been determined. Also, the bottom-most portion of the bolts terminate in a headed portion 22, which, in most instances, is enclosed by a resilient cap member 24 for the face-to-face contact with the support surface such as a floor and serves the dual purposes of providing a friction contact between the appliance and the floor to minimize movement of the machine, and provide a soft surface to prevent scratching the floor.

The lifting mechanism of the present invention is shown in FIG. 2 in its normally retracted position and includes a generally planar support plate 26 depending from the bottom wall 14 of the housing 12 by attaching means 28 which provide limited vertical movement of the support plate with respect to the bottom wall 14. The attaching means include guide bolts or rods 30 securely attached to the plate generally adjacent its peripheral edge as by inserting them through apertures in the support plate and capturing the support plate between opposed locking nuts 34, 36 and slidably received within aligned apertures (not shown) in the bottom wall 14 with the internal end having an enlarged headed portion 32 to prevent the bolt from exiting the bottom wall.

A coil spring 38 is interposed between and respectively attached to, as by a tack weld, the bottom wall 14 and the support plate 26 and coiled about the guide

rod 32 to normally bias the support plate to the retracted position shown. The support plate further has secured to its bottom face a plurality of caster means 40 of well known construction. An airtight inflatable diaphragm 42 is interposed between the bottom wall 14 and the support plate 26 and includes an air inlet hose 44 terminating in a valve means 46.

As seen in FIG. 1 but as more particularly pointed out in FIG. 3, the support plate of the present invention has a central opening generally to accommodate the central contour of the bottom wall 14 of the housing. Also for this reason, the inflatable diaphragm 42 of the preferred embodiment is generally donut-shaped and in many ways resembles the inner tube of the well-known pneumatic tire. Further, the valve means 46 associated with the air inlet 44 to the inflatable diaphragm also resembles the valve means generally associated therewith.

Under normal conditions, the appliance is stationarily supported on a floor or other support surface by resting on the friction pads 24 of the legs or foot bolts 22. However, with the present invention, upon desiring to move the appliance from one position to another, the diaphragm 42 is inflated by attaching to the valve means 46 any well known air pumping devices such as a hand pump or a small compressor such as is normally associated with household paint spraying device (either of which device is more than adequate to easily inflate the diaphragm to a pressure of approximately 5 pounds per square inch which, it has been found, is generally sufficient to expand the diaphragm to its operable support position) and the diaphragm is thereby inflated causing it to force the support plate and bottom wall member 14 to separate as opposed initially only by the spring 38 until the caster members have contacted the floor surface. Further, inflation of the diaphragm 42 causes further separation of the bottom wall and the support plate which from this point lifts the appliance from the foot bolts so that the weight of the appliance is supported on the support plate and consequently the 20 caster members through the diaphragm 42. It is desirable to inflate the diaphragm to the extent that the headed portions 32 of the guide rod 28 are seated against the bottom wall 14 to provide rigidity and alleviate any tilting which may result from the rather 25 non-symmetrically distributed weight of the appliance. It is to be noted that the amount of travel permitted by the guide bolts prior to it becoming seated on the bottom wall member 14 is more than sufficient to permit the 30 caster member 40 to come in contact with the floor when the adjustable support legs 16 have even been extended to their uppermost limit.

To facilitate moving the appliance once it is supported on the casters, a handle, not shown, can be provided on the appliance at a suitable location. Through this arrangement, the appliance can then be manually positioned in any desired location. Once it is in the desired position, the valve means can be opened to permit the diaphragm to deflate which in turn lowers the appliance so as to be once again supported on its legs and further deflation causes the support plate 26 to be retracted to its normally retracted position through the action of the coil springs 38. The machine thus again becomes generally stationarily supported upon its support legs 16.

It is apparent that through the lifting mechanism of the present invention, once the diaphragm 42 has been

properly inflated, the machine can be rolled or maneuvered to any other location without regard to a continuous air flow to maintain its elevated position and further it is manifestly apparent that the lifting mechanism of this invention does not require any complex lever or linkage arrangement to lift the appliance nor does it have any expensive valving or sealing requirements nor does it contain any fluid which may soil its surroundings should the diaphragm become punctured.

What we claim is:

1. A mechanism for transferring the support of an appliance from a generally stationary relationship on a surface to a generally easily movable relationship on the surface; said appliance having a bottom structural member generally adjacent said support surface, and means attached to said structural member providing frictional contact with said support surface for normally stationarily supporting said article wherein said transferring mechanism comprises:

a support plate interposed between said structural member and said support surface, said plate defining a first surface facing said structural member and an opposite surface facing said support surface;

means for attaching said support plate to said structural member for guided relative movement of one with respect to the other said attaching means including means for positively limiting said movement to a predetermined maximum amount;

a plurality of casters attached to said opposite surface of said plate; and,

inflatable means interposed between said structural member and said first surface of said plate for resiliently urging one away from the other to said predetermined amount which is sufficient to cause the casters to contact the support surface in an appliance weight bearing relationship whereby,

the weight of the appliance is transferred from said frictional support members to be supported on said casters for easy portability by said casters rolling on said support surface and said appliance is generally rigidly maintained in said caster supported position by abuttment of said movement limiting means.

2. Structure according to claim 1 wherein said mechanism also includes spring means attached to said plate and said structural member for resiliently urging relative vertical movement towards each other in opposition to said inflatable means.

3. Structure according to claim 2 wherein said inflatable means comprises an annular tube and includes valve means for connection to a source of pressurized fluid, said valve means when closed capable of maintaining said inflatable member in an inflated condition.

4. An appliance having a housing and support means associated with said housing for generally stationary support of said appliance on a support surface and a lifting mechanism for transferring the weight of said appliance from said stationary support means to caster structure associated with said lifting mechanism wherein said lifting mechanism comprises:

a support plate disposed between said housing and said support surface;

means for attaching said support plate to said housing for guided movement of said support plate with respect to said housing said attaching means including means for positively limiting said movement to a predetermined distance;

said caster structure attached to said support plate for rolling contact with said surface; and inflatable means positioned between said housing and said support plate for inflation to separate them said predetermined distance which is at least sufficient to raise said stationary support structure attached to said housing from contact with said support surface and abutt said movement limiting means.

5. Structure according to claim 4 including spring means connected between said plate and said housing

having a biasing force in opposition to the lifting force of said inflatable member for normally retaining said plate and said housing in generally close proximity when said inflatable member is not inflated.

6. Structure according to claim 5 wherein said inflatable member includes valve means for connection to a source of pressurized fluid, said valve means being capable of maintaining said inflatable member inflated when closed.
